UNITED STATES PATENT OFFICE.

GEORGE W. BENNETT, OF COLUMBUS, OHIO, ASSIGNOR OF ONE-HALF TO LEO E. DWYER,
OF COLUMBUS, OHIO.

TRAFFIC-SIGN.

1,331,691.

Specification of Letters Patent. Patented Feb. 24, 1920.

Application filed December 23, 1918. Serial No. 267,940.

To all whom it may concern:

Be it known that I, GEORGE W. BENNETT, a citizen of the United States, residing at Columbus, in the county of Franklin and State of Ohio, have invented certain new and useful Improvements in Traffic-Signs, of which the following is a specification.

This invention relates to traffic signs and is designed for use particularly at street crossing intersections where the normal traffic is heavy to such an extent that confusion would ordinarily arise without some directing instructions as to the proper course to pursue. Specifically, my invention is designed for use in the city streets for intermittently presenting stop and go signs.

In this connection, another object of my invention resides in a structure whereby all of the functions performed by the sign are accomplished automatically and further whereby the time interval of display of one sign may be varied as may be desired with respect to the succeeding display. In this manner, the thoroughfare having the greater amount of traffic may be permitted the go sign a longer time interval than the intersecting thoroughfare having perhaps a less amount of normal traffic.

With these objects in view, my invention consists in the combination and arrangement of parts, one embodiment of which is illustrated in the accompanying sheets of drawings wherein similar characters of reference designate corresponding parts and wherein,

Figure 1 is a view in side elevation of my improved structure with one side of the inclosing casing structure removed,

Fig. 2 is a view taken at right angles from that shown in Fig. 1, also with a portion of the casing removed, and

Fig. 3 is a horizontal section taken on line 3—3 of Fig. 2.

I have found it desirable to suitably close all of the gearing and driving mechanism employed in my invention and to this end, the casing 1 has been provided which also serves as the base or pedestal upon which the display sign 2 is mounted. This display sign, as shown, is of square formation and has been illustrated as being provided with glass faces 3 upon which the traffic legends are printed. Inasmuch as a square sign member has been shown, it follows that this particular design is ap-

plicable for two intersecting thoroughfares but the invention is not limited to this as the style of display member may very readily be changed to be in accordance with local conditions. Also, I preferably provide electric illumination for the interior of the sign inasmuch as the present embodiment has been illustrated as being driven by an electric motor. The wires leading to the electric bulbs located within the sign member pass through the centrally disposed conduit 4 while the hollow shaft 5 upon which the sign member itself is directly mounted is caused to pass through the hollow post 6 securely fastened at its lower end to the casing member 1 and being provided at its upper end with a bearing portion upon which the display member 3 may rotate.

As stated, the entire structure is illustrated as being driven by an electric motor 7, but the specific type of prime mover is not essential. The armature shaft 8 of this motor is extended and provided with a worm 9 which in turn meshes with a worm gear 10 suitably mounted upon the shaft 11. This shaft 11 is journaled in suitable bearing members 12 carried by the base of the casing and is further provided with a worm 13 at its opposite end. This worm in turn meshes with a second worm gear 14 mounted upon the upright counter shaft 15 also suitably journaled within the interior of the casing as shown at 16 and 17. This counter-shaft 15 in the present instance, carries a pair of segmental gears 18 and 19 designed to mesh with pinions 20 and 21 respectively mounted upon the hollow drive shaft 5. Segmental gears 18 and 19 are shown as being designed for the square type of display sign and to this end, their groups of teeth 22 are arranged diametrically opposite each other and are of a number which corresponds to one-quarter of the number of teeth on the pinions 20 and 21. By arranging the groups of teeth 22 diametrically opposite each other, it follows that one complete revolution of each of the gears 18 and 19 causes the sign to be moved twice, each time through one-quarter revolution. These gears 18 and 19 are suitably mounted upon their shaft 15 by means of the set screws 23 so that the relative arrangement of the various groups of teeth 22 may be altered in order that the time interval of display of one traffic legend may be varied with respect to 110

the succeeding display. In other words, by properly locating these groups of teeth 18 and 19, the go sign for one thoroughfare may be in position twice as long as the stop sign for the same thoroughfare. It will of course be understood that this time arrangement may be varied to suit conditions.

From the foregoing description, taken in connection with the accompanying sheets of drawings, it will be apparent that I have provided a type of traffic sign which does not require the personal attention of an attendant, usually a policeman. When once set in operation, the driving motor continues in such operation and the display legends may be automatically presented in any desired manner. By this is meant that the time interval of one display may be varied with respect to the succeeding display by the proper arrangement of the gears 18 and 19 upon their shaft.

What I claim is:

1. In a traffic sign, a display member capable of assuming a plurality of display positions, means for intermittently and automatically moving said member from one display position to another, and means whereby the time interval of one display may be varied with respect to the succeeding display.

2. In a traffic sign, a display member capable of assuming a plurality of display positions, a driving motor, gearing from said motor to said member, and a plurality of

segmental gears forming a part of said 35 gearing whose teeth are arranged to intermittently and automatically change said member from one display position to another, said segmental gears being mounted so that their positions may be varied to correspondingly vary the time of one display with respect to the succeeding display.

3. In a traffic signal, a casing, a continuously driven actuator mounted in said casing, a shaft disposed to be continuously rotated by said actuator, a rotatable signal operating member mounted in parallelism with said shaft, and adjustable means cooperative with said shaft and said member for intermittently rotating the latter and to 50 render uniform or irregular the time intervals between the shifting operations of said member.

4. In a traffic signal, a casing, a continuously driven actuator mounted in said casing, a pair of gear elements driven by said actuator, said elements being provided with spaced groups of teeth, a signal operating member, gears carried by said member and arranged for intermeshing engagement with 60 the teeth of said elements, whereby said member will be caused to intermittently rotate, and means permitting of varying the relative positions of the teeth of said gear elements to control the intervals of rest between the shifting of said member.

In testimony whereof I affix my signature.
GEORGE W. BENNETT.
